Primary Examiner — Susan Moon Lee(74) *Attorney, Agent, or Firm* — Studebaker & Brackett
PC(57) **CLAIM**

I claim the ornamental design for a circular hilt calf feeder, as shown and described.

DESCRIPTION

FIG. 1 is a perspective view of a circular hilt calf feeder in accordance with my new design, shown in a retracted configuration;

FIG. 2 is a rear perspective view thereof;

FIG. 3 is an enlarged front view thereof;

FIG. 4 is an enlarged rear view thereof;

FIG. 5 is a side view thereof, the opposite side, top and bottom views being identical;

FIG. 6 is a front perspective view of the circular hilt calf feeder, shown in an extended configuration;

FIG. 7 is a rear perspective view thereof; and,

FIG. 8 is a side view thereof, the opposite side, top and bottom views being identical.
